JOHANN STUMPF, OF BERLIN, GERMANY.

NONCONDENSING STEAM ENGINE.

Application filed November 10, 1920, Serial No. 423,201, and in Germany October 14, 1920.

The invention relates to steam engines, and is especially applicable to non-condensing steam engines.

The object is to provide improved method and means for transforming pressure energy of exhausting steam of a plural cylinder steam engine into kinetic energy and utilizing said kinetic energy derived from the exhausting steam of one cylinder in withdrawing residual exhaust from another cylinder. The invention is especially applicable to cylinders in which steam has a uni-directional flow.

The invention comprises the method of utilizing the entire pressure of the exhaust of one cylinder at the point of release, that is the point at which the exhaust port begins to open, to draw exhaust steam from another cylinder.

This method involves an overlap of the exhaust periods of two or more cylinders in such manner that the maximum velocity in the exhaust of one cylinder is available for acting upon the residual exhaust of another cylinder.

The invention also comprises improved means for effecting the method above defined, including an ejector and means for preventing the expansion or loss of velocity until after the exhaust has passed the ejector; nozzle formations for preventing loss in transforming initial pressure energy into kinetic energy, and diffuser formations for changing kinetic energy into pressure energy in order to discharge against the atmosphere, and in combining with the means above recited, an elongated piston for covering the main exhaust ports at all times except near the end of the stroke. The invention also includes exhaust valves so timed that the exhaust of one cylinder will open at a proper interval before the final closing of the exhaust of another cylinder. The invention also covers other details and formations herein particularly described.

Referring to the drawings which illustrate merely by way of example, suitable and preferred means for effecting my invention;—

Fig. 1 is a diagram showing the time of opening of the exhaust ports of a twin cylinder uniflow engine.

Fig. 2 is a steam diagram of said engine.

Fig. 3 is a diagram showing the time of opening of the exhaust ports of a triple cylinder uniflow steam engine.

Fig. 4 comprises three indicator diagrams,

with cut-off at three different positions of the piston.

Fig. 5 is a cross-section through the cylinders and a smoke box of a locomotive.

Fig. 5^a is a top plan view of formation 11.

Fig. 6 is a part elevation part section of a cylinder and valve gear therefor.

Fig. 7 is a diagrammatic section showing a two-cylinder engine with the cranks at 90°, with 75% release, Fig. 7^a showing the crank arrangement.

Fig. 8 is a similar view showing a two-cylinder engine with cranks at 90°, with 90% release, with auxiliary exhaust, Fig. 8^a showing the crank arrangement.

Fig. 9 is a similar view showing a three-cylinder engine with cranks at 120° with 90% release, Fig. 9^a showing the crank arrangement.

Similar numerals refer to similar parts throughout the several views.

In the diagram, Fig. 1 of a crank circle of a twin cylinder uniflow engine, is shown the time of opening the exhaust ports, controlled by the piston, with an advance of 25% in the lead of the exhaust, with cranks at 90°.

In this diagram, *a* and *b* represent the circular motion of the engine when the exhaust ports of one cylinder are open, and *c* and *d* represent the circular motion of the engine when the exhaust ports of the other cylinder are open.

It will thus be seen that the opening of the exhaust ports of opposite cylinders overlap to the extent of the shaded parts *e*, *f*, *g* and *h*; or that the exhaust port of one cylinder is opened before the exhaust port of the opposite cylinder is closed.

The entire initial energy of the exhaust at the point of release is utilized in drawing residual exhaust steam from the opposite cylinder just before its exhaust port closes.

The diagram, Fig. 2, shows an indicator card in black lines, with the expansion curve carried to the exhaust pressure shown by the shaded portion. The shaded portion *A* shows the amount of steam exhausted during the simultaneous opening of the exhaust ports of both cylinders and represents the energy which is utilized to draw off the residual steam of the opposite cylinder and drop the pressure in the opposite cylinder as indicated at *l*, *m*. *C* represents the increase in the work done in the cylinder due to the lowering of the pressure from *l* to *m*.

The shaded portion B indicates that part of the steam left in the cylinder, which is exhausted by its own pressure after the exhaust port of the opposite cylinder has been 5 closed.

The diagram, Fig. 3, shows the time of opening of the ports controlled by the pistons of a triple cylinder uniflow steam engine with an advance of ten per cent in the lead 10 of the exhaust and with cranks at 120°. The arcs M, N, P, Q, R and S show the time in the cycle when the exhaust valves are open. The shaded sections show the overlapping of the exhaust valve openings. The 15 time of opening of the exhaust of one cylinder is always partially covering that of another, so that, at all times, residual steam is drawn out from one or two other cylinders.

The diagram, Fig. 4, represents three indicator diagrams or cards, with cut-off at three 20 different positions of the piston. A cut-off at 44% gives sufficient exhausting energy to produce an exhaust pressure of 0.68 atm., abs., corresponding to a vacuum of 32%, if 25 ample losses by friction etc., are assumed in the calculation. A cut-off at 60% or 70% will certainly entail a vacuum of 50%. This, in combination with the commencement of the compression at 75%, allows a clearance 30 space of the same size as used in ordinary locomotives. The vacuum produced in a triple cylinder engine will always be larger than in a twin cylinder engine, as the residual steam is better drawn out by the other 35 cylinders than by the one cylinder. The short length of the usual exhaust pipe will not allow too much suction upon the residual steam of the same cylinder.

In a triple cylinder engine the exhaust 40 will also show the greatest uniformity, and, when used with a locomotive, will produce a good intensive and effective combustion. There will be a substantial reduction of 45 steam consumption and a substantial increase of the capacity of the engine. A cut-off at different positions of the piston will entail different vacua and different compressions as indicated in Fig. 4.

In the cross-section view, Fig. 5, the exhaust 50 nozzles 3 and 4 are placed in the cylinder wall. The area is first smoothly reduced and then smoothly and gradually enlarged. Only two nozzles, 3 and 18, and 4 and 16 are arranged in the wall of each cylinder; one being continued by a pipe leading 55 to the ejector-union 7, 8, 9, 10, 11, and the common smoke stack 15, 16, 17. The other nozzles 18 and 19 lead by other pipes 20, 21 to heating devices not shown.

In the triple cylinder engine, three exhaust 60 pipes meet at the union, the cross-section of which is almost tripled in comparison with the cross-section of one single cylinder exhaust pipe.

In Fig. 6, the cylinder is shown with

single beat valves 22, 22', a Walchaert gear and an actuating cam with rollers. The resulting motion of the Walchaert gear is communicated by rod 23 to the lever 24 upon shaft 25, mounted in a casing 26, and bearing a swinging cam 27 provided with curved faces acting upon the rollers attached to swinging levers 28, 28'. These levers transmit motion to horizontal slide pieces 29, 29', which push the spindles of the single beat 70 valves 22, 22'. The pistons 31 are movable in a cylinder formation 32 arranged in the central part of the casing 26. Steam or compressed air may be introduced into the space between the pistons 31, by means of a 80 pipe 30, to press them apart, thus engaging elements 29, 29' and opening the inlet valves in order to remove all resistance for the locomotive when drifting or empty running.

By making the advance in the lead of the 85 exhaust in a uniflow cylinder as large as 25%, the length of the piston may be reduced and consequently the length and weight of the cylinder. In fact the cylinder has about the same weight as an ordinary cylinder. 90 The single beat valves are tight against high pressure, are very light and simple and need no lubrication.

The exhaust ports 3 and 4 in the cylinder 95 walls, which are controlled by the piston, are made in the form of steam nozzles which have the effect of transforming pressure energy of the steam into kinetic energy. The form of these nozzles, as shown in Fig. 5 at 3 and 4, as well as the form of the piston as shown in Fig. 6, are made to cooperate so as to give good nozzle efficiency during the time of partial uncovering of the ports. Both may be adapted as to shape and size 100 so as to give those cross-sections of free area required by the decreasing difference of pressure.

By combining the exhaust pipes of two or more cylinders, in an ejector like formation, a partial vacuum is created in one cylinder 110 by the action of the exhaust from another cylinder or cylinders. The position of the cranks at ninety degrees in a twin cylinder engine and of one hundred and twenty degrees in a triple cylinder engine will favor 115 this suction action, if sufficient advance on the lead of the exhaust is used; twenty-five per cent will answer all requirements in two cylinders, and ten per cent in three. This will correspond to a release at seventy-five and 120 ninety per cent of the stroke of the piston, generally required for locomotives with two or three cylinders respectively. By release or point of release is meant the point at which the exhaust port begins to open, 125 thereby releasing the exhaust steam from the cylinder. It is important that the entire pressure of the exhaust at the point of release, be utilized in order to produce the maximum velocity, and that the exhaust 130

shall not be permitted to expand beyond that incident to its passage through pipes 5 to 6 to the ejector. Therefore the exhaust connections are so designed that there shall be 5 no pressure or velocity losses, due to unnecessary expansion.

That part of the exhaust steam flowing with the highest speed from one cylinder, will just meet with that part of the exhaust 10 steam from the other cylinder flowing with the lowest speed.

The nozzle formation is shown as having its most restricted part in the cylinder wall, as at 3 and 4, Fig. 5. This position is optional 15 so long as it is located before the ejector union so that all pressure energy will be transformed into speed energy before said union, where the cross-section should be enlarged to secure good suction. After 20 the ejector union, the cross-section of the combined exhaust pipe should be gradually increased up to the highest end, which shall have the largest cross-section, as shown in Fig. 5. As a rule the smallest cross-section 25 is in the cylinder wall, the largest at the end of the combined exhaust pipe. This is altogether different from the usual practice in locomotives.

In the diffuser thus realized in the combined exhaust pipe, the equalized flow of exhaust steam is transformed into exhaust steam with less speed and higher pressure. Just sufficient speed is left to produce sufficient air draft in the furnace. 35 Exhaust steam and combustion gases are thus mixed in the formation 17, Fig. 5, forming a flow of mixture which will be partially transformed into pressure energy in the diffuser of the chimney 15.

It is important properly to proportion the size of the smallest area of the different nozzles at the cylinders. For the average production of steam, with about twenty-five per cent advance in the lead of the exhaust, 40 they should offer such area as to secure a flow of steam during nearly the whole time of the opening of the exhaust port. In this manner the greatest uniformity in the combined flow of steam and the greatest sucking action will be obtained.

It is preferable, when the exhaust is used to produce draft in the furnace, to use two diffusers, one 10, after having taken up the residual steam of a cylinder or cylinders, 45 and the other 15, after having taken up the combustion gases.

The partial vacuum in the exhaust of the uniflow cylinder, will in itself increase the efficiency and capacity of the steam engine, 50 because the required clearance space is substantially reduced, the compression also is changed, so that great compression is combined with small cut-off and small compression with large cut-off, as it should be.

55 All exhaust piping should be made with

smooth internal surfaces, with no corners or sudden changes in direction and area. The arrangement should be such that the transformation of the residual pressure energy into speed energy, the transmission of 70 the same, the impact of steam from one cylinder with the residual steam of another cylinder and the impact of steam with the combustion gases, and the transformation of the resulting speed energy of the mixture 75 into pressure energy at atmospheric pressure is secured with the maximum efficiency.

Where it is desired to secure a lengthened time for the exhaust at the cylinder, near the ends, valves may be provided which are 80 controlled by the piston, as shown in Fig. 8.

While the invention is especially applicable to non-condensing steam engines, it will be obvious to those skilled in the art, that the improvements herein described will 85 also be applicable to other engines using expansive medium having high initial pressure and subsequent expansive force.

While the invention is especially adapted for locomotives, it may be used to great advantage for similar machinery, such as steam tractors, steam vehicles and common exhaust steam engines with two or more cylinders.

It is known that non-condensing uniflow 90 steam engines ordinarily require a large clearance space on account of the great length of compression and on account of the pressure with which the compression is started. There is consequently the disadvantage of excessive 100 clearance space and a large steam consumption. This disadvantage can be substantially reduced either by reducing the terminal exhaust pressure or by increasing the initial pressure or by combining both.

105 The advantage therefore of the present method and means over the common practice, is that, instead of an over-pressure, a partial vacuum, up to one-half atm. is created in the exhausting cylinder. This 110 decreases the steam consumption and yet leaves sufficient velocity of exhaust steam, through the smoke stack to produce the required draft in the fire-box of the locomotive.

115 The energy for accomplishing this result is taken from that part represented in the diagram Fig. 2, as lost by incomplete expansion.

What I claim is:—

1. In a plural cylinder engine, the combination of means comprising exhaust ports and passages having nozzle formations to prevent loss in transforming the initial pressure energy of the exhaust to kinetic energy and means comprising an ejector for utilizing 125 said kinetic energy derived from the exhaust of one cylinder to draw the exhaust from another cylinder.

2. In a plural cylinder engine, the combination of means comprising exhaust ports 130

and passages having nozzle formations to prevent loss in transforming the initial pressure energy of the exhaust to kinetic energy, means comprising an ejector for utilizing said kinetic energy derived from the exhaust of one cylinder to draw the exhaust from another cylinder, and means comprising an additional diffuser for changing kinetic energy back to pressure energy for discharging against atmosphere.

3. In a plural cylinder engine having main exhaust ports controlled by the power piston operating so that, when exhausting, there shall be no opening of the main exhaust port or ports, except the exhaust opening from the exhausting side of the cylinder, the combination of means forming an ejector common to all exhaust ports, and port controlling means so timed that the exhaust

from one cylinder will operate to withdraw the exhaust steam from another cylinder.

4. In a plural cylinder engine having main exhaust ports controlled by the power piston operating so that, when exhausting, there shall be no opening of the main exhaust port or ports, except the exhaust opening from the exhausting side of the cylinder, the said cylinders also having supplementary exhaust ports and valves controlling the same, the combination of means forming an ejector common to all exhaust ports, and port controlling means so timed that the exhaust from one cylinder will operate to withdraw the exhaust steam from another cylinder.

In testimony that I claim the foregoing as my invention I have signed my name.

JOHANN STUMPF.
